United States Patent Office.

FREDERICK WILLIAM EGER AND HENRY H. KUNZE, OF PHILADELPHIA,
PENNSYLVANIA.

Design No. 4,688, dated February 28, 1871.

DESIGN FOR A BED-QUILT.

The Schedule referred to in these Letters Patent and making part of the same.

To all whom it may concern:

Be it known that we, FREDERICK WILLIAM EGER and HENRY H. KUNZE, both of the city and county of Philadelphia and State of Pennsylvania, have invented a new and useful Design for the Configuration of a Bed-Quilt; and we do hereby declare the following to be a clear and exact description of the nature thereof, reference being had to the accompanying photographic illustrations.

In carrying out our invention, the design may be described as consisting of blocks A and B.

Each block A is subdivided, by means of a cross, *c c*, into sections, *a a*.

Each block B is subdivided, by means of a cross, *d d*, into sections, *b b*.

Thus the sections of one block and the cross of the adjacent block are prominent.

This alternate arrangement of the blocks A B pre-

sents a pleasing contrast, and the effect of the union of blocks is neat, tasty, and attractive.

To increase the ornamental appearance of the quilt the crosses *c c* may have blocks, *e*, arranged at their centers, while the crosses *d d* may have open spaces, *f*, at their centers.

Having thus described our invention,

What we claim is—

The design for the configuration of a bed-quilt, consisting of the series of blocks A B, subdivided by crosses *c d*, and alternating with each other, as shown.

FRED. WM. EGER.
HENRY H. KUNZE.
